UNITED STATES PATENT OFFICE.

FRANK A. STECHER, OF ROCHESTER, NEW YORK, ASSIGNOR TO STECHER LITHOGRAPHIC COMPANY, OF ROCHESTER, NEW YORK, A CORPORATION OF NEW YORK.

DESIGN FOR A PAPER-BOX BLANK.

SPECIFICATION forming part of Design No. 35,615, dated January 28, 1902.

Application filed December 13, 1901. Serial No. 85,859. Term of patent 7 years.

To all whom it may concern:

Be it known that I, FRANK A. STECHER, of Rochester, in the county of Monroe and State of New York, have invented and produced a new and original Design for Paper-Box Blanks; and I do hereby declare the following to be a full, clear, and exact description of the same, reference being had to the accompanying drawing, forming a part of this specification, and to the reference characters marked thereon.

The leading feature of my design consists in the shape and outline of a blank for paper boxes, of which the figure of drawing is a plan view of a blank illustrating my design.

The design consists of a central rectangular panel A, having at its sides narrow elongated panels a, from which extend panels B, having their upper and outer corners rounded, as shown, and the panels are provided with lines of incision b. At one end the panels a are provided with small flaps a'. The upper and lower sides of the central panel are bounded by narrow elongated panels c and d, and extending from the former is a panel C, 25 provided at its outer corners with the ears c'. Arranged in said panel is an incision-line E. The flap D extends from the panel d and is formed with irregularly-curved sides converging and forming the end portion F, across 30 the base of which extends a score-line f. Between the adjacent edges of the several panels are creased or scored lines g.

Having described my invention, what I claim as new, and desire to secure by Letters 35 Patent, is—

The design for a box-blank, substantially as shown and described.

In testimony whereof I have signed my name to this specification in the presence of 40 two subscribing witnesses.

FRANK A. STECHER.
